SHEET FEEDING MECHANISM

Paul E. Pearson, Chicago, Ill., assignor to Continental Can Company, Inc., New York, N. Y., a corporation of New York

Original application May 11, 1940, Serial No. 334,657. Divided and this application January 21, 1941, Serial No. 375,100

17 Claims. (Cl. 271—62)

The invention relates generally to sheet feeding mechanisms wherein are provided means for delivering sheets one at a time to machine structures such as lithographing or sheet slitting machines, pneumatically actuated sheet gripper devices for lifting sheets one at a time from a pack maintained at a level for being engaged by said devices and presenting the lifted sheets to said delivering means, and means for lifting the pack to and maintaining it at said elevation, and said invention primarily seeks to provide novel means for lifting the sheet packs to and maintaining them at the level from which they are fed. This application constitutes a division of my co-pending parent application entitled Sheet feeding mechanism, filed May 11, 1940, Serial Number 334,657.

An object of the invention is to provide a machine of the character stated embodying novel means for supporting a pack of sheets and novel means for imparting rapid traverse movement to said supporting means upwardly to the effective sheet presenting position, or downwardly, to a position for receiving a replenished pack supply, said last named means including a driving motor, a reversible clutch, and novel means for shifting the clutch to a neutral position each time said supporting means attains its upper effective or lower limit position.

Another object of the invention is to provide novel means for automatically lifting the pack of sheets through small increments of movement so as to constantly present the uppermost sheet of the pack in position for being engaged by the gripping and lifting units.

Another object of the invention is to provide a machine embodying traverse movement imparting equipment including a reversible clutch and actuator means therefor, and means for automatically locking the actuator means against movement during automatic feeding of the pack for presenting the uppermost sheets successively in position for being engaged by the gripping units.

Another object of the invention is to provide novel sheet pack position controlling means and devices for rendering said means ineffective during the imparting of rapid traverse movement upwardly or downwardly to the pack or the pack supporting means.

Another object of the invention is to provide means for automatically presenting the uppermost sheets of the pack successively in position for being engaged by the gripper units and including novel ratchet and pawl devices and au-

tomatically operable means for releasing the pawl from the ratchet each time the proper height of the pack has been attained.

Another object of the invention is to provide a machine of the character stated in which is included pack supporting means, means including a motor for lifting and lowering the supporting means to and from pack presenting positions, novel means including ratchet and pawl devices for lifting the pack to successively present uppermost sheets thereof for engagement by lifting devices, and manually operable means for releasing said pawl and automatically starting said motor.

With these and other objects in view which will more fully appear, the nature of the invention will be more clearly understood by following the description, the appended claims, and the several views illustrated in the accompanying drawings.

In the drawings—

Figure 1 is a front elevation, parts being broken away and in section.

Figure 2 is a fragmentary upper left side elevation, parts being broken away and in section.

Figure 3 is a fragmentary vertical cross section illustrating the driving connections for the cam shaft and the feed roll shaft.

Figure 4 is a fragmentary vertical section illustrating the feeder pawl position controlling means.

Figure 5 is a left side elevation of the parts shown in Figure 4.

Figure 6 is an enlarged fragmentary vertical cross section illustrating the position of the sheet pack lift controlling switch.

Figure 7 is a detail longitudinal section illustrating the reversible clutch structure.

Figure 8 is a detail vertical cross section taken on the line 8—8 on Figure 7.

In the example of embodiment of the invention herein disclosed, 5 designates the skid platform on which the pack 6 of sheets to be fed are supported. In the mounting of these skids and sheet packs in proper cooperative relation with the feeding devices of the machine the individual skid platforms are rolled into place in the machine over rollways 7 which are engaged by the laterally spaced, longitudinally disposed supporting legs 8 depending from the skid platforms.

The lateral edges of the platforms 5 overlie rollways 9 which are disposed longitudinally on the C-shaped lifting and lowering frame 10 and facilitate mounting and removal of said plat-

forms, the frame 10 being open at the front in the manner best illustrated in Figure 1 of the drawings.

Four lifting and lowering chains 11 are provided and each is secured at its lower end as at 12 at one of the four corners of the frame 10. Each chain passes over a sprocket 13, two such sprockets being secured upon each of the two shafts 14 which are disposed in parallel spaced relation one along each upper side of the machine framing. Each shaft 14 is rotatable in bearings 15 provided therefor in a longitudinal end framing unit 16, and each of these frame units is supported at its front end on a corner post or standard 17, and at the rear, indirectly, on framing generally designated 18, each said unit being secured as at 19 to a housing unit structure 20 which is in turn supported by said framing 18. The housing units 20 serve as supporting means for a rear cross frame member 21 which is secured as at 22 to said housing units.

Each shaft 14 has a worm wheel 23 secured thereon within the respective housing unit 20 and is rotatably supported in bearings 24 provided in said housing 20. A cross shaft 25 is rotatably supported at its ends in suitable bearings provided therefor in the housing units 20, and within each housing this cross shaft carries a worm gear 26 which meshes with the respective worm wheel 23. The shaft 25 extends beyond the housing unit 20 at the left side of the machine and has a ratchet wheel 27 affixed thereto. It will be obvious that as rotation is imparted to the ratchet wheel 27 it will be transmitted through the shaft 25 and the worm gears affixed thereon to the worm wheels 23 and the shafts 14 on which they are mounted. Rotation of the shafts 14 in one direction or the other will serve to lift or lower the chains 11 and the skid platform 5 and sheet pack 6 supported on the supporting frame 10. The power transmitting connections just referred to serve to impart rotation to the shaft 14 in a direction for lifting the chains only and the means for imparting movement to the ratchet wheel 27 and the means for imparting rotation to the shaft 25 in the opposite direction for effecting a lowering of the supporting frame 10 will be described in detail hereinafter.

At the rear of the machine there is mounted a sheet pack limiting wall generally designated 28 and best indicated in Figure 1 of the drawings.

Each housing unit 20 includes upper and lower shaft bearings 29 and 30, and the housing unit at the right side of the machine includes a shaft bearing 31 disposed between the bearings 29 and 30.

A cam shaft 32 is rotatably supported in the aligned bearings 29 in the housing units 20 and carries a gear 33 to which rotation is imparted by a smaller gear 34 secured upon a driver shaft 35 rotatably supported in the housing unit bearing 31, the shaft 35 being driven through a bevel gear couple 36 from any suitable power input source, preferably from the sheet slitting machine or a lithographing or other machine to which the sheet feeding machine is connected in cooperative relation.

The driver shaft 35 also carries a larger gear 37 which meshes with and drives a small gear 38 secured upon a sheet feed roll shaft 39 rotatably supported in the aligned housing unit bearings 30. The shaft 39 also carries a sprocket or pulley 40 forming a part of a roll driving couple.

The cam shaft 32 carries an adjustably mounted timing or forwarding roll separator cam 41, an adjustably mounted double sheet detector cam 42, and a forwarding cam 43 which imparts oscillatory movement to the sheet feeding units which will be referred to hereinafter.

The cam shaft 32 also carries a bevel gear 44 which meshes with a similar gear 45 secured upon the lower end of a vertically disposed actuator shaft 46 forming a part of the master pneumatic control valve generally designated 47 and which is secured upon and centrally of the cross frame member 21 previously referred to.

The shaft 39 is disposed just behind the rear limit wall 28, and an intermediate bearing 48 is provided for centrally supporting this shaft. A plurality of pulleys 49 are secured to and spaced along the shaft 39 and the peripheries of these pulleys extend above the level of the upper edge of the wall 28. Two upper roll and guide supporting rolls 50 also are secured upon this shaft and one is disposed between the pulleys 49 at opposite sides of the center bearing 48. This shaft also carries a gage roll 51 which is secured adjacent the center of said shaft and close to the central supporting bearing 48.

The driven sheet feeding rolls 52 are opposed by drop rolls 53 carried by crank arm equipments 54 one of which is actuated by the roll separator cam 41 to effect an alternate lifting of the rolls 52 to receive a sheet therebeneath and dropping of said rolls 52 to effect a feeding away of said sheet. The sheets thus fed are delivered from the machine on tapes or belts 55 which pass over the pulleys 49, and the gage roll 51 is opposed by a detector or gage roll 56 which, together with the detector cam 42, forms a part of a double sheet detecting and ejecting mechanism disclosed in detail in the parent application hereinbefore referred to and forms no part of the invention claimed herein.

A shaft 58 traverses the machine toward the rear and above the sheet pack and is rockably mounted in bearings 57 secured to the machine framing. Another shaft 58 is disposed parallel and to the rear of the shaft 58 at the same elevation and is rockably supported in frame bearings 59. The shaft 58 has one end extended and fitted with an actuator crank 60 which carries a roller 61 engaged by the forwarding cam 43. Another crank arm 62 is secured to the shaft 58, and an anchored spring 63 attached to this crank serves to yieldably hold the roller 61 against the cam 43. Gripper unit supporting arms 64 depend in aligned pairs from the shafts 58 and 58 and are held in parallel relation by gripper unit carrying links 65 pivotally connected thereto as at 66. Each of the links 65 includes a split clamp collar 67 for removably securing and supporting a sheet gripping and lifting unit generally designated 68.

In addition to the sheet feeding gripper units 68 just above referred to, four intermediate grippers 69 are provided for lifting and holding sheets as they are being fed, thereby to prevent scratching of said sheets by dragging them over the underlying pack. These intermediate grippers are swingably mounted as at 70, so that they can swing freely in the direction in which the sheets are being fed, and are returned to their initial position after each sheet feeding movement by spring equipments 71. Sheet lifting gripper units generally designated 72 are provided at the front end of the machine adjacent the standards 17, and these units serve to lift

the front corners of the sheets prior to each sheet feeding operation, the lifting grip being released just prior to the actual feeding movement of the sheets.

Upon the free ends of side hanger rods 78 pivotally mounted on the framing is supported a cross shaft or tube 74, the latter being secured as at 75 to the free ends of said rods. Suitable rigid supporting means 76 serves to hold the U-shaped frame formed by the members 73 and 74 a definite distance above the pack of sheets.

The shaft or tube 74 carries a clamp sleeve 77 near each end and each sleeve includes a rearwardly extending clamp collar having a gripper unit receiving bore therein disposed at a slight angle with respect to the vertical so that the axis of the units clamped in the collars converge inwardly and rearwardly, or inwardly and in the direction in which the sheets are fed. Each sleeve 77 also includes a pair of forwardly directed clamp collars 78 having bores therein for receiving and securely clamping a pair of air blast tubes 79. One tube of each pair terminates in a vertically disposed nozzle 80 positioned for directing a blast of air against the sheets at the upper portion of the pack, and the other tube of each pair terminates at a slightly higher level in a horizontally disposed air blast nozzle 81 similarly directed toward the upper extremity of the pack. In addition to those just described, a pair of air blast nozzles (not shown) may be suitably supported at the rear upper side portion of the pack for directing blasts of air against the uppermost sheets of the pack at that portion also.

The tube or shaft 74 also supports two or more intermediately disposed clamp sleeves 82 for each of which a guide plate 83 depends in position for engaging the edges of the sheets at the upper portion of the pack and retaining the desired spaced relation between said sheet edge portion and the nozzles 80, 81.

During the operation of the machine the pack of sheets is automatically lifted through small increments of movement to constantly present the uppermost sheet of the pack at a proper elevation for being engaged by the gripper units. When almost all of the sheets of a pack have been fed one by one therefrom, it becomes desirable to mount a new pack in the machine, and in order to accomplish this it is necessary to provide a temporary support for the small number of sheets yet remaining in the pack and to lower the pack skid supporting frame to a position for receiving a fresh skid and pack and to return the supporting frame to an elevated position for presenting the newly supplied pack in cooperative relation with the gripping elements.

In the machine herein disclosed, means is employed for accomplishing this lowering and lifting of the skid and pack supporting frame by rapid traverse movements. The normal lifting of a pack through small increments of movement is accomplished by rotation of the cam shaft 32 and the cross shaft 25, power being applied to these shafts from an outside source as previously described. The means for imparting the rapid traverse movements just referred to include an individual motor and reversible clutch equipment which will now be described.

A motor 84 is secured as at 85 to depend from a reversible clutch unit generally designated 86 which is in turn mounted as at 87 on the machine framing.

Any suitable reversible clutch unit may be employed and the one herein illustrated includes a driver shaft 88 rotatable in bearings 89 in the casing or housing and driven by sprocket and chain connections 90 from the shaft of the motor 84. The unit also includes a driven shaft 91 rotatable in bearings 92 provided therefor in the casing, and this shaft has sprocket and chain connection 93 with the worm shaft 25 hereinbefore referred to so that the rotation imparted in one direction or the other to the shaft 91 will be transmitted to the shaft 25 for effecting a relatively rapid lifting or lowering of the chains 11 which pass over the sprockets 13 secured upon the shafts 14 hereinbefore described.

A large spur gear 94 is loosely mounted on the shaft 91 and is constantly driven by a small pinion 95 on the driver shaft 88. A smaller spur gear 96 is loosely mounted on the shaft 91 and is constantly driven in a direction opposite the direction of rotation of the gear 94 by an idler gear 97 supported on the unit housing and enmeshed with the gear 96 and with the gear 98 secured upon the shaft 88.

Each of the gears 96 and 94 carries a clutch head portion 99, and these head portions are selectively engaged by a clutch element 100 splined at 101 on the shaft 91. The clutch head 100 is shifted in one direction or the other on the shaft 91 by a shifter fork 102 secured to a shaft 103 rockably mounted in the unit casing and which is extended outside the casing and equipped with an actuator crank 104. The crank 104 is link-connected as at 105 with the central 35 vertical arm 106 of a 3-arm actuator lever. The lever includes two arms extended in opposite, generally horizontal directions and one of these arms 107 is pivotally connected as at 108 with a vertically disposed slideable control bar 109 40 which is slide-guided as at 110 and includes an outwardly extended top lug 111 and a similarly extended bottom lug 112. The lugs 111 and 112 are presented for engagement by the pack supporting skid at upper and lower limits of its 45 travel.

The other generally horizontal arm 113 of the lever is link-connected as at 114 with a crank member 115 secured upon an actuator shaft 116 rockably supported as at 117 on the 50 machine frame along the left side of the machine. The shaft 116 also carries two vertically depending manually operable actuator handles 118. The shaft 116 also has a large plate 119 affixed thereto, and this plate is provided with 55 a vertically disposed latching recess 120 which is vertically, centrally disposed and open at the bottom.

A thrust link 121 having crank connection with the shaft 32, as by connection with the forwarding cam 43 as at 122, is connected to one arm 123 of a bell crank lever which is oscillatable about the shaft 25 on which the ratchet wheel 27 is affixed. The other arm 124 of the bell crank lever has a ratchet wheel engaging pawl 125 pivoted at its free end, and it will be obvious that when the bell crank lever 123, 124 is oscillated with the pawl in engagement with the ratchet wheel 27, increments of movement will be imparted to the shaft 25, and from it to the pack lifting chains 13 in the manner hereinbefore described.

A housing 126 is secured as at 127 to the machine framing, and a pawl position controlling rod 128 is vertically reciprocable in bearings 129 provided in said housing. The rod is connected

with the pawl 125 by a link 130 which is pivoted to the rod as at 131 and slot and pin connected as at 132 to said pawl.

The rod 128 is secured as at 133 to the upper end of the core 134 of a solenoid 135, the lower end of said core being connected to a link 138 which is slot and pin connected as at 137 to a switch actuator rod 138.

The switch actuator rod 138 is vertically slideable in bearings 139 provided in the housing and has a pin 140 projected therefrom for engagement in the fork end of a crank member 141 rockably mounted as at 142 on the housing and having an actuator handle 143 secured thereto. The handle 143 is equipped with a spring detent 144 releasably insertable in receiving recesses provided in the housing for the purpose of securing the rod in its raised or lowered position, the lowered position of the rod being illustrated in Figure 5 of the drawings. The rod 138 also carries a pair of adjustably spaced switch actuator fingers 145 engageable with a switch actuator 146 rockably mounted at 147 and engageable with stop and start buttons of a switch 148 connected in the power circuit 149 serving the motor 84. Thus each time the rod 138 is lowered to the position illustrated in Figure 5 of the drawings, it will close the switch 148 and start operation of the motor 84, and when this rod is raised the operation of this motor will be automatically stopped.

The rod 138 also carries a switch actuator fork 150 engageable with the actuator lever 151 of a switch 152 connected in the circuit connections 153 serving the solenoid 135.

A collar 154 is secured centrally of the cross shaft or tube 14 and carries a bracket 155 equipped with a cylinder 156 having a bore 157 in which a valve plunger 158 is vertically slideable. The plunger is threaded at its upper end and carries a stop collar 159. The bracket also includes a lug portion 160 vertically spaced from and overlying the upper end of the cylinder and which has a threaded bore in which a socket plug 161 is adjustably mounted. A compression spring 162 is interposed between the plug 161 and the upper end of the plunger and normally holds the plunger down at the lower limit of its movement determined by the stop collar 159.

The cylinder includes a pair of aligned cross ports 163 one of which connects at one side with a pressure line 164 from a suitable source of air pressure and the other of which connects with a pressure line 165 leading to a control valve. The plunger also includes a cross duct 166 and a longitudinal side recess 167 which normally communicates between the pressure line 165 and a venting duct 168 opening laterally through the cylinder wall. It will be obvious that when the plunger is lifted against the action of the spring 162 the cross port 166 will open communication between the cross ducts 163 of the cylinder and allow air pressure to flow from the line 164 into the line 165.

At its lower end the plunger 158 carries a bracket member 169 having a cylinder 170 at its lower end in the axial bore of which a plunger 171 is vertically slideable. The plunger 171 has a limited amount of vertical movement in the bore of the cylinder 170, and movement in the upward direction is resisted by a compression spring 172 surrounding the plunger within the cylinder. The amount of movement of the plunger in both directions is limited by abutment heads 173 threadably mounted on the

plunger. The plunger terminates at its lower end in a stirrup 174 which carries a roller 175 adapted to be engaged by the uppermost sheet of the sheet pack 6.

5 A switch 176 in which the contacts are held separated or in circuit breaking relation is mounted on the bracket 169 directly above the plunger 171. The contacts of this switch are normally held separated by engagement of the 10 plunger 171. This switch is connected in the power circuit lines 153 which serve the solenoid 135 and, as stated, the circuit is normally broken through this switch except when the plunger 171 is lowered by reduction of the predetermined 15 top level of the sheet pack by feeding of individual sheets therefrom. When the plunger is thus lowered it will permit the switch contacts to engage and complete the solenoid energizing circuit. Each time the top level of the pack is 20 reduced below the predetermined level by the feeding of individual sheets therefrom, the plunger 171 will be lowered a sufficient distance to permit the switch contacts to close and complete the circuit which energizes the solenoid 135 and thereby effect a re-engagement of the 25 pawl with the ratchet wheel 27 so that the pack will be fed upwardly a sufficient distance to again effect a breaking of the solenoid energizing circuit and another retraction of the 30 pawl, it being understood that each time the solenoid energizing circuit is broken the rod 128 will fall by gravity and effect a retraction of the pawl.

It will be noted by reference to Figure 5 of the drawings that the rod 128 carries a latch lug 177 which engages the lower bearing 129 and limits downward movement of the rod whenever the solenoid 135 is not energized, and when the rod is lifted by the energized solenoid to operably position the pawl this lug engages in the latch notch 120 in the latch plate 119 affixed to the rock shaft 116 and serves to lock the shaft against movement so that the clutch is held in neutral, thus making it impossible to 40 apply power to the devices for lifting and lowering the pack in rapid traverse movement while the normal lifting of the pack by small increments and the feeding of sheets therefrom is proceeding.

50 The pressure line 165 connects with the lower end of a pivotally mounted cylinder 178 secured upon the frame adjacent the shaft 116. A piston 179 is vertically reciprocable in the cylinder and is attached to a plunger 180 which extends upwardly from the cylinder and has slot and pin connection at 181 with a crank 182 secured upon the clutch control shaft 116. Whenever the pack is lifted high enough to cause the plunger port 166 to register with the cross ports 163 in the control cylinder 156, as by initial lifting of the pack by the rapid traverse lifting equipments, air pressure flowing through the lines 164 and 165 will force the piston 179 upwardly, and the upward movement of the plunger 180 will 55 actuate the crank 182 to rock the shaft 116 and shift the clutch to neutral.

70 In operation, in the initial loading of the machine, a skid 8 having a sheet pack thereon is rolled over the rollways 7 into position over the C-shaped supporting frame 10 and with the pack 8 against the rear limiting wall 28. By adjusting the handle 143 the machine attendant can 75 depress the rods 128 and 138. It will be understood that when these rods are depressed the pawl 125 will be moved out of engagement with

the ratchet wheel 27. Depression of the rod 138 actuates the switch 152 to break the circuit through the solenoid energizing circuit 153 and will also actuate the switch 148 for automatically closing the motor control circuit 149 and setting the motor 84 into operation.

By now manually actuating one of the control handles 118 toward the left, as viewed in Figure 1 of the drawings, the rock shaft 116 and the crank and link connections 115, 114, 113, 106, 105, 104 and 102 will be actuated so as to properly shift the clutch to impart rapid upward traverse movement to the pack supporting frame and the pack thereon by rotation of the chain actuating shafts 25 through the transmission connections 93.

As the skid and pack thereon reach the intended upper limit the skid will engage the bar projection 111 and mechanically rock the lever 107, 106, 113 and thereby effect a shifting of the clutch to the neutral position. This skid effected automatic upward rapid traverse control is supplemented by the pack effected control equipment including the cylinder 156 and roller 175. As the pack top attains the desired level for proper cooperation with the sheet gripping and feeding devices, it will engage the roller 175 and force the plunger 158 upwardly so as to effect cross communication between the air pressure lines 164 and 165 through the cross duct 166 in said plunger. This pressure communication will effect a lifting of the piston 179 and an actuation of the crank 182 effective to shift the clutch to the neutral condition in the manner hereinbefore described.

With the sheet pack thus presented with its top portion in proper cooperative relation with the gripping and feeding units, the sheets are successively lifted one by one from the top of the pack and presented to the feeding-away equipments hereinbefore referred to. Each time double or superposed sheets are lifted and presented to the feed rollers they are ejected by the ejector mechanism hereinbefore referred to, and, as the level of the pack is lowered, the pack is automatically raised by small increments so as to maintain the desired spaced relation between the sheet gripping and lifting units and the uppermost sheet of the pack. The master valve 47 controls the flow of air through and the evacuation of the lines leading to the gripping units, in a manner described in detail in the parent application Serial No. 334,657 hereinbefore referred to, so that the pressure introduced into the units is effective to force the suction cups against the uppermost sheet as the arms 64 reach the limit of their swing forwardly or in the sheet receiving direction. The gripper cups are evacuated at the time they contact the sheet and the pressure effective to present the cups is released just after the suction gripping of the sheet has been effected so that the cups are lifted to the positions illustrated in Figure 1 of the drawings.

The cups of the units 72 at the front corners of the sheets are lifted and lowered only, and the units are not movable in the sheet presenting or feeding direction. The suction gripping action of these cups is discontinued immediately after gripping of the front end of the sheet has been effected, and, as previously stated, the sheet corners are turned upwardly, as indicated in Figure 1, so that the air blasts delivered through the nozzles 80, 81 will serve to overcome any tendency of the underlying sheet to adhere to and be lifted with the uppermost sheet. As the

arms 64 are swung forwardly, the units 68 present the rear edge of the lifted sheet between the feeder rolls, which are separated in the manner hereinbefore described at the moment at which the presentation is effected, and are thereafter permitted to move together so that the feeding of the sheet out of the machine can be effected. During the rearward movement of the units 68, the intermediate units generally designated 69 swing rearwardly with the gripped sheet and serve to hold it elevated out of contact with the underlying sheet, thereby preventing dragging and scratching of the sheets. The suction within the cups of the units 68 and 69 is released just before the arms 64 start their return swing and after the feeder rollers have gripped the presented end of the sheet.

This individual feeding of sheets continues, and each time the top level of the pack falls below the predetermined level the circuit 153, effective to energize the solenoid 135, is energized by a lowering of the plunger 171 and the rod 128 is lifted to cause the pawl 125 which is being constantly oscillated to engage and impart increments of movement to the ratchet wheel 27 effective to again lift the pack to the desired elevation. When this desired elevation is attained the circuit 153 will be again broken by lifting of the plunger 171 in the manner hereinbefore described.

Whenever the sheet pack has been reduced to approximately two inches in height, a pack supporting fork 183 is slipped under the pack through openings provided for that purpose in the skid and will serve to temporarily support the remaining sheets of the pack while the supporting frame is being lowered to receive a new skid and pack supply. The rear end of the fork 183 rests upon the rear wall 28, and the front end thereof is supported upon brackets 184 secured to and projecting from the frame standards 17.

By now moving the rod 138 downwardly by actuation of the hand crank 143, the operator can disconnect the pawl 125 and render ineffective the solenoid 135 and the control equipments therefor in the manner hereinbefore described, and also actuate the switch 148 for energizing the motor circuit and starting operation of the motor 84. By now shifting one of the control levers 118 to the right, as viewed in Figure 1 of the drawings, the clutch can be set to effect a rapid traverse movement downwardly of the pack supporting frame. As the frame reaches its lower limit the skid will engage the bottom lug 112 on the bar 109 and shift the lever 107, 106 to again shift the clutch to the neutral position, thereby discontinuing downward movement of the supporting chains 13. After a new pack has been mounted on the support the control devices can be actuated to lift the pack to the proper elevation in the manner hereinbefore described.

The master valve 47 is illustrated and described in detail in parent application Serial No. 334,657, together with all connections thereof with the suction and pressure air sources and need not be described in detail herein since it forms no part of the invention herein claimed. The same is true of the separate valve which controls the flow of pressure air to the winding nozzles. This separate valve is generally designated 185, is mounted at 186 on the cross frame member 21, and is actuated in timed relation to the sheet feeding devices by cams 187 mounted on the cam shaft 32. See Figures 1 and 5. As is described

in said parent case, the valve 185 can be rendered ineffective by manipulation of a rocker cam 188 mounted on a shaft 189 rockable in bearings 190 on the machine framing and equipped at each end with a hand crank 191. At the left hand end the shaft 189 also carries a crank 192 which is link-connected as at 193 with a crank 194 mounted on the rotary valve actuator shaft 195. The shaft 189 carries a rotary pilot valve turnable, as described in said parent application, from an active position, in which it opens communications between the master valve 47 and the suction source, to an inactive position in which it closes off said suction source communication and bleeds the valve to atmosphere. The valve shaft 195 also carries a hand crank 196 which is held in its elevated or active position, or in a lowered inactive position by a spring detent 197.

The crank lever 196 is connected by a slotted link 198 with an extension from the crank member 60 which is actuated by the forwarding cam 43 for imparting sheet presenting movement to the arm 64 and the gripper units 68 carried thereby. It will be observed that the slot in the link 198 will permit normal operation of the crank 60, but when the lever 196 is swung downwardly the link 198 will lift the roller 61 out of contact with the cam 43 for silencing the sheet grippers and discontinuing the sheet forwarding operation. This movement of the lever also shifts the rotary pilot valve to its cut off position, and, through the medium of the crank and link connections 194, 193 and 192, the shaft 189 is rocked to move the cam 188 to the position for rendering the valve 185 ineffective and cutting off pressure communication with the winding devices.

This manipulation of the pilot valve cuts off both the pressure air and the vacuum supply, 40 and stops the feeding of sheets without stopping the machine. By this manipulation of the pilot valve the pressure chamber in the master valve 47 is suitably bled so that the grippers will not tend to partially operate on the next cycle.

It is of course to be understood that the details of structure and arrangement of parts may be variously changed and modified without departing from the spirit and scope of my invention.

I claim:

1. In a machine of the character described, means for supporting a pack of sheets horizontally beneath a sheet lifting and presenting means, means for imparting intermittent increments of pack lifting movement to said supporting means to maintain the pack at a predetermined level, and means for imparting rapid traverse movements to the supporting means during initial placement and replacement of sheet packs and including a driving motor, a reversible clutch, pack controlled means for controlling the operation of the increment movement imparting means, means for shifting the clutch to operative and inoperative positions, and means associated with said pack controlled means for positively locking the clutch shifting means against shifting movement whenever the increment movement imparting means is in operation.

2. In a machine of the character described, sheet pack supporting means for supporting a sheet pack while sheets are being fed one by one therefrom, rapid traverse means for moving the supporting means during initial placement and replacement of the pack, means for auto-

5 matically moving the pack toward the feeding means through small increments as sheets are successively fed from the pack, and pack controlled means for positively locking the rapid traverse means against functioning while the increment movement imparting means is functioning.

3. In a machine of the character described, sheet pack supporting means for supporting a sheet pack while sheets are being fed one by one therefrom, a pair of shafts disposed in parallel relation and having sprockets thereon, chains depending from the sprockets and secured to said supporting means, a cross shaft having worm gear and worm wheel connections at its respective ends with said parallel shafts, a ratchet wheel on said cross shaft, means including a pawl engageable with and disengageable from said ratchet wheel for imparting small increment movements to said cross shaft, means for at times imparting continuous rapid traverse effecting movements to said cross shaft in one direction or another, means for independently operating said small increment and rapid traverse movement imparting means, pack controlled means for controlling engagement of the pawl with and disengagement of the same from the ratchet and means associated with the pack controlled means for locking the rapid transverse movement imparting means against movement when the pawl is in engagement with the ratchet wheel.

4. In a machine of the character described, sheet pack supporting means for supporting a sheet pack while sheets are being fed one by one therefrom, means including a motor and a power circuit therefor for imparting rapid traverse movements to the supporting means during initial placement and replacement of the pack, means including a ratchet and pawl for automatically moving the pack toward the feeding means through small increments as sheets are successively fed from the pack, and means movable to energize the motor circuit and connected with said pawl so as to move the pawl to an inoperative position whenever the motor is energized.

5. In a machine of the character described, sheet pack supporting means for supporting a sheet pack while sheets are being fed one by one therefrom, means including a motor and a power circuit therefor for imparting rapid traverse movements to the supporting means during initial placement and replacement of the pack, means including a ratchet and pawl for automatically moving the pack toward the feeding means through small increments as sheets are successively fed from the pack, means movable to energize the motor circuit and connected with said pawl so as to move the pawl to an inoperative position whenever the motor is energized, said rapid traverse movement imparting means also including a reversible clutch associated with the motor for driving the rapid traverse movement imparting means in one direction or another, manually operable means for shifting the clutch, and means locking the shifting means against movement whenever the pawl is in operative position and releasable upon movement of the pawl to its inoperative position for freeing said shifting means.

6. In a machine of the character described, sheet pack supporting means for supporting a sheet pack while sheets are being fed one by one therefrom, means including a motor and a power

circuit therefor for imparting rapid traverse movements to the supporting means during initial placement and replacement of the pack, means including pack engaged switch and a control circuit for automatically moving the pack toward the feeding means through small increments as sheets are successively fed from the pack, and manually operable means for simultaneously making or completing the motor circuit and breaking the control circuit.

7. In a machine of the character described, sheet pack supporting means for supporting a sheet pack while sheets are being fed one by one therefrom, means including a ratchet and pawl for lifting the pack support through small increments as sheets are fed from the pack, and a solenoid connected with the pawl and with a control circuit including a switch which is closed each time the pack is lowered to a predetermined elevation to energize the solenoid and place the pawl in driving contact with the ratchet.

8. In a machine of the character described, sheet pack supporting means for supporting a sheet pack while sheets are being fed one by one therefrom, means including a ratchet and pawl for lifting the pack support through small increments as sheets are fed from the pack, and a solenoid connected with the pawl and with a control circuit including a switch which is closed each time the pack is lowered to a predetermined elevation to energize the solenoid and place the pawl in driving contact with the ratchet, means including a motor and a power circuit therefor for imparting rapid traverse movements to the supporting means during initial placement and replacement of the pack, said rapid traverse movement imparting means also including a reversible clutch associated with the motor for driving the rapid traverse movement imparting means in one direction or another, manually operable means for shifting the clutch, and means locking the shifting means against movement whenever the pawl is in operative position and releasable upon movement of the pawl to its inoperative position for freeing said shifting means.

9. In a machine of the character described, sheet pack supporting means for supporting a sheet pack while sheets are being fed one by one therefrom, means including a ratchet and pawl for lifting the pack support through small increments as sheets are fed from the pack, and a solenoid connected with the pawl and with a control circuit including a switch which is closed each time the pack is lowered to a predetermined elevation to energize the solenoid and place the pawl in driving contact with the ratchet, means including a motor and a power circuit therefor for imparting rapid traverse movements to the supporting means during initial placement and replacement of the pack, said rapid traverse movement imparting means also including a reversible clutch associated with the motor for driving the rapid traverse movement imparting means in one direction or another, manually operable means for shifting the clutch, and means locking the shifting means against movement whenever the pawl is in operative position and releasable upon movement of the pawl to its inoperative position for freeing said shifting means, and means movable to energize the motor circuit and simultaneously break the control circuit and connected with said pawl so as to move the pawl to an inoperative position whenever the motor is energized.

10. In a machine of the character described, sheet pack supporting means for supporting a sheet pack while sheets are being fed one by one therefrom, means including a ratchet and pawl for lifting the pack support through small increments as sheets are fed from the pack, and a solenoid connected with the pawl and with a control circuit including a switch which is closed each time the pack is lowered to a predetermined elevation to energize the solenoid and place the pawl in driving contact with the ratchet, means including a motor and a power circuit therefor for imparting rapid traverse movements to the supporting means during initial placement and replacement of the pack, and means movable to energize the motor circuit and simultaneously break the control circuit and connected with said pawl so as to move the pawl to an inoperative position whenever the motor is energized.

11. In a machine of the character described, a sheet pack support for supporting a sheet pack while sheets are being fed one by one therefrom, means for elevating the pack as sheets are fed therefrom, means including a shiftable clutch for imparting rapid traverse movement to the support upwardly or downwardly during the initial placement or the replacement of the pack, means for manually shifting the clutch to initiate traverse movement in either direction, and means for automatically shifting the clutch to neutral when the support reaches a predetermined position in its travel in either direction.

12. In a machine of the character described, a sheet pack support for supporting a sheet pack while sheets are being fed one by one therefrom, means for elevating the pack as sheets are fed therefrom, means including a shiftable clutch for imparting rapid traverse movement to the support upwardly or downwardly during the initial placement or the replacement of the pack, means for manually shifting the clutch to initiate traverse movement in either direction, and means engaged by the support means for automatically shifting the clutch to neutral when the support reaches a predetermined position in its travel in either direction.

13. In a machine of the character described, a sheet pack support for supporting a sheet pack while sheets are being fed one by one therefrom, means for elevating the pack as sheets are fed therefrom, means including a shiftable clutch for imparting rapid traverse movement to the support upwardly or downwardly during the initial placement or the replacement of the pack, means for manually shifting the clutch to initiate traverse movement in either direction, means actuated by support engagement for automatically shifting the clutch to neutral when the support reaches a predetermined position in its downward travel, and means actuated by engagement of the top of the pack for automatically shifting the clutch to neutral when the pack reaches a predetermined position in its upward travel.

14. In a machine of the character described, a sheet pack support for supporting a sheet pack while sheets are being fed one by one therefrom, means for elevating the pack as sheets are fed therefrom, means including a shiftable clutch for imparting rapid traverse movement to the support upwardly or downwardly during the initial placement or the replacement of the pack, means for manually shifting the clutch to initiate traverse movement in either direction, and

fluid pressure operable means actuated by engagement of the top of the pack for automatically shifting the clutch to neutral when the pack reaches a predetermined position in its upward travel.

15. In a machine of the character described wherein is provided a pack support, means including an energized power circuit for lifting the support by small increments of movement as sheets are fed successively off the top of the pack, and means for imparting rapid traverse movements to the support during initial placement or replacement of packs and including a clutch manually actuated for initiating movement upwardly or downwardly, control means actuated by upward engagement by the pack being elevated and comprising a plunger structure, means actuated upon limited upward movement of the plunger structure for breaking the energized power circuit, and means actuated by a greater upward movement of the plunger structure for shifting the clutch into neutral.

16. In a machine of the character described wherein is provided a pack support, means including an energized power circuit for lifting the support by small increments of movement as sheets are fed successively off the top of the pack, and means for imparting rapid traverse movements to the support during initial placement or replacement of packs and including a clutch manually actuated for initiating movement upwardly or downwardly, control means actuated by upward engagement by the pack being elevated and comprising a clutch shifting

5 cylinder and piston structure, a stationary bracket having a vertical plunger bore and a fluid pressure duct traversing the bore and connected with a source of pressure and with said cylinder and piston structure, said plunger having a cross bore normally disposed below and out of registry with said duct, a bracket carried by said bore, a second plunger having limited vertical movement in the plunger bracket and disposed for engagement by the top of a pack of sheets on said support, a normally closed switch connected in said power circuit and actuated each time the second plunger is lifted a predetermined amount to break said circuit, said second plunger, the plunger bracket and the plunger being moved vertically at the conclusion of each upward rapid traverse to cause the cross bore and duct to register and the piston to effect a shifting of the clutch to neutral.

17. In a machine of the character described, means for supporting a pack of sheets, means for imparting intermittent increments of vertical movement to said supporting means, and means for imparting rapid transverse movements to the supporting means and including gear mechanisms, a motor operated in one direction only for driving said gear mechanisms, a pair of clutches for selectively connecting the gear mechanisms with the supporting means, and means for automatically shifting the clutches to neutral at each upper and lower limit of the supporting means movement.

PAUL E. PEARSON.
